UNITED STATES PATENT OFFICE.

MARIE D. McDONALD, OF PORTLAND, OREGON.

WOMAN'S HAT.

1,345,547.

Specification of Letters Patent.

Patented July 6, 1920.

Application filed September 19, 1919. Serial No. 325,015.

To all whom it may concern:

Be it known that I, MARIE D. McDONALD, a citizen of the United States, and a resident of Portland, county of Multnomah, and 5 State of Oregon, have invented a new and useful Improvement in Women's Hats, of which the following is a specification.

Women's hats are awkward things to hold, especially those made with wide rims. The 10 only way it can be held conveniently, is by the brim, which has a tendency to throw the hat out of shape, also tending to disarrange the trimming and soil the materials. Furthermore, the hat cannot be hung from a 15 peg like a man's hat. To remedy these difficulties is the object of my invention.

I attain my objects by providing in the interior of the hat, a band or hand-strap into 20 which the hand may be inserted for holding the hat; and adjacent one end of the strap, I provide a loop by which the hat may be hung from a peg.

The strap and loop are secured to the lining and are arranged as illustrated in the 25 accompanying drawings, in which;

Figure 1 is a perspective of a woman's hat with my hand-strap and loop secured to the lining thereof;

Fig. 2 is a similar view showing the hat 30 as being held by a hand inserted in the strap; and

Fig. 3 is a similar view showing the hat suspended from a peg by the loop provided at one end of the hand-strap.

Referring first to Fig. 1, *a* is the crown, *b* 35 the brim, and *c* the lining in the interior of the crown of the hat.

To the lining is sewed a strap *d*, by means 40 of stitches at its ends as at *e*, *e'*. In practice it is convenient to sew the ends of the strap *d*, in place by the same stitches which sew the margin of the crown *c'* of the lining to the sides *c*² thereof, in this way, not only producing a neat effect, but saving labor and 45 firmly securing the ends of the hand-strap in place. Furthermore, the hand-strap is secured to the crown piece of the lining by intermediate stitches *f*, *f'*, so located as to make the loop of the hand-strap of a length 50 relative to the width of a hand; in other words, rendering the hand-strap of convenient size for inserting the hand in position for holding the hat as illustrated in Fig. 2.

The hand-strap must be of substantial 55

width so that it may be firmly held by the hand.

At one end of the strap *d* is formed a loop *g*, so that the hat may be hung from a peg *h* as illustrated in Fig. 3. 60

The edges of the strap of the loop should be neatly bound as illustrated at *i*, by so doing, not only giving to the whole a neat and attractive appearance, but stiffening the hand-strap, and holding it in loop form, 65 convenient for inserting the hand. The hand-strap and loop, if neatly made do not detract from the finish of the hat, but to the contrary, in my judgment, give the hat a more tailored finish. The loop *g* may be 70 used for holding a price ticket or for memorandum or other article, carried by the wearer of the hat.

A wide hand-strap is especially desirable 75 in displaying the hat to a customer, inasmuch as it will permit the holding of the hat firmly, causing it to hang gracefully from the hand and avoiding the necessity of handling the hat with the hands, which handling often soils the material of which 80 the hat is made and disarranges the trimmings.

The length of the loop of the hand-strap relatively to the width of the hand is also important, as above mentioned, in the same 85 connection, because a narrow strap would be harder to hold, and would have a tendency to slip its position on the hand.

From Figs. 2 and 3 it is obvious how my 90 invention facilitates the holding or hanging of a hat; and how the holding loop of the hand-strap offers a great advantage in holding the hat for display to a customer.

I claim:

1. In a hat provided with a lining, a hand- 95 strap stitched at its ends to the lining being arranged parallel with the latter, the hand-strap being of substantial width, the hand-strap being stiffened so that the portion between its ends will have a tendency to assume and maintain a loop form, and a loop at one end of said hand-strap, such loop being adapted for hanging the hat from a peg. 100

2. In a hat provided with a lining, a hand- 105 strap stitched at its ends to the lining being arranged parallel with the latter, the hand-strap being of substantial width, the stitches securing the hand-strap to the lining being located at the fastening of the margin of the crown-piece of the lining to the sides of 110

the latter, transverse supplemental stitches, spaced inward from said first mentioned stitches, securing the hand-strap adjacent its ends to the lining, thereby forming a loop of convenient length relative to the width of the hand, for the purpose specified.

3. In a hat provided with a lining, a hand-strap stitched at its ends to the lining being arranged parallel with the latter, the hand-strap being of substantial width, the stitches securing the hand-strap to the lining being located at the fastening of the margin of the crown-piece of the lining to the sides of the latter, transverse supplemental stitches, spaced inward from said first mentioned stitches, securing the hand-strap adjacent its ends to the lining, thereby forming a loop of convenient length relative to the width of the hand, for the purpose specified, the hand-strap being stiffened so that the portion between said supplemental stitches will have a tendency to assume and maintain a loop form.

4. In a hat provided with a lining, a hand-strap stitched at its ends to the lining being arranged parallel with the latter, the hand-strap being of substantial width, the stitches securing the hand-strap to the lining being located at the fastening of the margin of the crown-piece of the lining to the sides of the latter, transverse supplemental stitches, spaced inward from said first mentioned stitches, securing the hand-strap adjacent its ends to the lining, thereby forming a loop

of convenient length relative to the width of the hand, for the purpose specified, the hand-strap being stiffened by reinforcement along its edges so that the portion between said supplemental stitches will have a tendency to assume and maintain a loop form.

5. In a hat provided with a lining, a hand-strap stitched at its ends to the lining being arranged parallel with the latter, the hand-strap being of substantial width, the stitches securing the hand-strap to the lining being located at the fastening of the margin of the crown-piece of the lining to the sides of the latter, transverse supplemental stitches, spaced inward from said first mentioned stitches, securing the hand-strap adjacent its ends to the lining, thereby forming a loop of convenient length relative to the width of the hand, for the purpose specified, the hand-strap being stiffened so that the portion between said supplemental stitches will have a tendency to assume and maintain a loop form.

6. In a hat provided with a lining, a hand-strap stitched at its ends to the lining in parallel relation therewith, and a loop at one end of said hand strap adapted for hanging the hat from a peg.

7. In a hat provided with a lining, a hand-strap stitched at its ends to the lining in parallel relation therewith.

MARIE D. McDONALD.
